US00D657239S

(12) **United States Design Patent**
Gavrilenkov et al.

(10) **Patent No.:** US D657,239 S
(45) **Date of Patent:** ** Apr. 10, 2012

(54) **ORAL CARE PACKAGING**

(75) Inventors: **Valentin Valentinovich Gavrilenkov**,
Saint-Petersburg (RU); **Maxine Jane
Walter**, Egham (GB); **Mahis Zadorian**,
Egham (GB)

(73) Assignee: **The Procter & Gamble Company**,
Cincinnati, OH (US)

(**) Term: **14 Years**

(21) Appl. No.: **29/360,406**

(22) Filed: **Apr. 26, 2010**

(30) **Foreign Application Priority Data**

Dec. 17, 2009 (WO) 526219901

(51) **LOC (9) Cl.** **09-03**

(52) **U.S. Cl.** **D9/432**

(57) **CLAIM**

The ornamental design for oral care packaging, as shown and described.

DESCRIPTION

FIG. 1 is a perspective view of oral care packaging showing our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof; and,

FIG. 7 is a right side elevational view thereof.

The special dot-dash broken lines shown in FIGS. 1, 2 and 4 define the bounds of the claimed design and form no part thereof.

1 Claim, 2 Drawing Sheets
